UNITED STATES PATENT OFFICE.

CHARLES McGOWAN, GUSTAF PETERSON, AND ARTHUR A. LUND, OF SUSANVILLE,
CALIFORNIA.

CAR-DOOR ROLLER.

Application filed December 18, 1922. Serial No. 607,573.

To all whom it may concern:

Be it known that we, CHARLES McGOWAN, GUSTAF PETERSON, and ARTHUR A. LUND, citizens of the United States, residing at 5 Susanville, in the county of Lassen and State of California, have invented certain new and useful Improvements in Car-Door Rollers, of which the following is a specification.

Our invention relates to an improvement 10 in car door rollers specifically adapted for attachment to car doors, whereby the loading of the car is expedited and further, wherein the present roller is so devised as to fit any type of car door and to be substantially adjustable thereon, or rather, between the car door and the door post.

The primary object of the invention resides in the provision of such a device that is comparatively simple of construction, 20 easy of installation and highly efficient of operation.

The nature and advantages of the invention will be better understood when the following detailed description is read in connection with the accompanying drawings, 25 the invention residing in the construction, combination, and arrangement of parts as claimed.

In the drawings forming part of this application, like numerals of reference indicate similar parts in the several views, and wherein:—

Figure 1 is a view in front elevation of a 30 device constructed in accordance with the present invention, the same being shown in position upon a car.

Figure 2 is a longitudinal cross sectional view upon the line 2—2 of Figure 1.

Figure 3 is a view similar to Figure 2, 40 but taken upon the line 3—3 of Figure 1.

Figure 4 is a fragmentary top plan view of the device, partly in cross section, the roller being shown in full and dotted line positions, and

45 Figures 5 and 6 are sectional view taken on the lines 5—5 and 6—6, respectively, of Figure 1, looking in the direction of the arrows.

In the drawings, we have shown our device applied to a convenient type of freight car A, provided with the usual sliding door B thereon. The roller includes a relatively elongated angle bar 5, preferably U-shape in cross section, and being longitudinally slotted adjacent its outer ends as at 6, fur-

ther, the bar is also longitudinally slotted at its central portion as at 7.

Slidably disposed in each end slot 6 is a bolt 8, having a headed or hooked inner end 9 and being screw threaded for a portion of its length as at 10. Pivotally secured to the upper end of each bolt 8, is the yoked end 11 of a swinging arm 12, which arm has formed on its outer end a hook or head 13, extending in an opposite direction to the hook or head 9 of its complementary bolt 8. Each of the legs constituting the yoked ends of the arms 12 are hooked as at 14 for engagement with a cross pin 15 carried by the bolts 8 for limiting the backward swinging movement of the arms 12. Nuts 16 with integral handle members 17 are adapted for screw threaded arrangement upon each bolt 8, and the inner face of each nut 16 has a washer 18 formed thereon, for wedging engagement with the adjacent face of the bar 5 in a manner hereinafter described.

In view of the above description, it will be readily understood that the bar 5 may be conveniently adjustably supported between one vertical edge of the car door B, and the adjacent vertical edge of the door opening or post in the car A. As shown in Figure 2, one of the end bolts 8 is turned within its complementary slot 6, and is so disposed therein, as to allow the headed or hooked end 13 of the swinging arm 12 to engage over the edge of the car door opening or door post, where it may be rigidly secured by the nut 16. The other bolt 8 at the opposite end of the bar 5, has its hooked end 9 engaging over the edge of the door B. The arm 12 in this instance, being swung inwardly as shown in Figure 3. This bolt 9 is also rigidly secured between the door and bar 5 by the securing nut 16 thereon.

As before mentioned, the bar 5 is of U shape, and slidably disposed between the top and bottom flanges forming this bar, is a metallic block 19 projecting outwardly of the flanges of the U bar 5, as more clearly shown in Figures 5 and 6 and longitudinally shouldered at 20 upon its upper and lower edges for close contact with the ends of the flanges of the U bar.

Extending vertically through the projecting portion of the block 19, and slightly off center, as shown, is a bolt 21, headed at its upper end as at 22, and screw threaded at its lower end as at 23. Between the

headed end of the bolt, and the upper surface of the block 19 and adjacent flange of the bar 5, is a relatively elongated U-shaped roller carrying bracket 23, which has an opening 24 therein, for receiving the said bolt 21. This roller carrying bracket 23 has secured thereto an arm or plate 25, which engages over the head 22 of the bolt 21 as more clearly shown in Figures 1 and 5, for preventing rotation of this bolt within the block 19. The vertical end legs comprising this roller carrying bracket are each provided with a screw threaded opening 26 therein, for receiving set screws 27, the inner ends 15 of which are pointed as at 28, and these set screws are adjustable within the openings of the bracket legs by nuts 29. The pointed ends 28 of these set screws 27 are adapted for engagement within the coupled ends of 20 what may be termed an annular shaft 30. Engaging over this shaft is a fiber roller 31, which is preferably crowned or convex as shown in Figure 4. The opposite ends of the shaft 30 are screw threaded, and the 25 roller 31 is maintained thereon by nuts 32 engaging over the screw threaded ends of the shaft and having openings 33 in the periphery thereof for receiving the lugs of a spanner wrench or the like whereby these 30 nuts may be separated.

The lower screw threaded end of the bolt 21 is adapted to receive a nut 34 having a handle 35 formed thereon, and it will be readily understood that when this nut is 35 screwed away from the block 19 and lower flange of the U-bar 5, the roller bracket 23 may be adjusted to any angle desired, to be secured in its adjusted position by screwing the nut 34 upon the bolt 21.

40 The block 19 has another bolt 36 extending therethrough and at right angles to the bolt 21. This bolt is headed at 37 at one end and screw threaded at 38 at its opposite end. This screw threaded bolt is adapted for projection through the central slot 7 in the bar 5. Adapted for screw threaded engagement upon the screw threaded end of this bolt is a nut 39 adapted to be screwed up on the bolt when the roller 31 has been 45 properly adjusted on the bar 5.

In view of the above description, it will be readily seen that the bar 5 may be adjusted and secured in its adjusted position at any desired point between one edge of the 55 car door post, and further, that each of the bolts 8 and the arms 12 may be so adjusted in the slots 6 of the bar as to have either the head 9 of the bolt or the head 13 of its asso-

ciate arm engage with either the edge of the car door or the car door post. Further, 60 these bolts may be longitudinally adjusted with respect to the bar 5 for obvious purposes, and again the roller 31 may be adjusted at any angle desirable with respect to the opening in the car body. 65

While it is believed that from the foregoing description, the nature and advantages of the invention will be readily apparent, we desire to have it understood that we do not limit ourselves to what is herein 70 shown and described, and that such changes may be resorted to when desired as fall within the scope of what is claimed.

What we claim as new is:—

1. A device of the class described comprising a supporting bar of channel form having longitudinally extending elongated slots in the web thereof and at its ends, bolts extending through and slidably disposed in said slots and having nuts threaded upon the outer ends thereof, said bolts being provided with laterally extending inner ends forming clamping arms, a block slidably disposed in the channel of the supporting bar and projecting beyond the free longitudinal edges of the flanges of said supporting bar, said supporting bar having a further central longitudinally extending elongated slot in the web thereof, a bolt extending through the last named slot and through said block, a nut upon the outer end of the bolt for adjustably clamping the block against sliding movement, and a roller supporting bracket pivotally mounted on said block. 90

2. A device of the class described comprising a supporting bar of channel form having longitudinally elongated slots in the web thereof and adjacent the ends of the same, bolts extending through said slots and having laterally projecting inner ends facing in one direction to provide clamping arms, arms pivoted to the inner ends of the bolts and having hooked free ends extending laterally in a direction opposite to that in which said clamping arms project, ends upon the outer ends of said bolts for clamping the same adjustably in said slots, and a roller carrying bracket adjustable longitudinally on the supporting bar intermediate its ends. 105

In testimony whereof we affix our signatures.

CHARLES McGOWAN.
GUSTAF PETERSON.
ARTHUR A. LUND.
